UNITED STATES PATENT OFFICE

FRANK DITCHFIELD, OF CLEVELAND, OHIO, ASSIGNOR TO YOUNGSTOWN STEEL DOOR CO., OF CLEVELAND, OHIO, A CORPORATION OF OHIO

RAILWAY-CAR DOOR

Application filed March 7, 1928. Serial No. 259,682.

This invention relates to improvements in railway car doors.

In the use of railway box cars there is a gradually increasing use of steel doors, which has demonstrated the desirable qualities of doors of this type, and has also disclosed the necessity for providing rugged reinforcements for the doors, particularly at the forward and rearward edges thereof, which will 10 be capable of withstanding the severe service to which the doors are subjected in actual use. This must be accomplished without unduly increasing the weight of the doors and without increasing the cost of production. The 15 front and rear edges of the doors especially are subjected to rough usage, incident to opening and closing the doors, which tends to cause distortion of the edges thereof to such an extent that the doors will not operate 20 properly and deteriorate rapidly unless expensive repairs are made at frequent intervals. In order to strengthen the front and rear edges of metallic doors, many expedients have been tested, one of which resides in the 25 provision of relatively heavy commercial rolled sections secured along the edges of the doors. This expedient solves many of the difficulties above mentioned, but great difficulty has been encountered in securing the 30 sections to the sheet metal of the door in such manner that they will stand up in service, a particularly important disadvantage lying in the tendency of the heavier commercial sections to rotate about their longitudinal axes 35 under the blows which they sustain, hence permitting distortion of the door edges, which they are designed to prevent, the displacement of the sections serving to tear out the sheet metal at the points of connection 40 with the sections, resulting in serious injury to the door. Many additional problems are involved in producing reinforced constructions at the front and rear edges of the door, and in connection with which the spark and 45 weather seals may be of sufficiently rugged construction to stand up in service.

An object of this invention is to provide a reinforced door construction in which the body portion is made up of reinforced sheet 50 metal panels, and wherein the front and rear

edges of the door comprise relatively heavy metal bars formed in a novel manner especially adapting them for connection with the sheet metal body portion of the door as to present a rugged construction well able to 55 withstand the heavy blows to which the edges of the door are subjected, and which are so formed and connected to the sheet metal body portion as to successfully resist any rotating or twisting tendencies of the bars 60 about their longitudinal axes, this result being accomplished through the particular formation of the bars and the manner in which they are fabricated with the sheet metal of the 65 body portion of the door.

Another object of the invention is to provide a front edge construction wherein the sheet metal of the door is off-set and a bar, originally of T section, has its stem extending substantially at right angles to the plane defined by the main body portion of the door, with the free end of the stem bent at an angle and secured to the off set body portion, while the oppositely extending head flanges of the 70 T section are secured to the sheet metal of the 75 body portion at each side of the off set portion thereof, providing in effect a hollow tubular formation at the edge of the door, the majority of sides of which are defined by the 80 flanges of the reinforcing bar.

Another object of the invention is to provide a similar reinforced construction at the rear edge of the door, with the additional feature that a spark or weather seal is formed integrally with the reinforcing bar, providing a specially strong and rugged construction 85 well able to withstand hard service.

A still further object of the invention is to provide reinforced front and rear edge constructions for the so-called outside type of 90 double sliding doors wherein the reinforced edge construction of one of the doors is utilized for supporting means to which the nail-block is to be adapted to be secured.

Other and further objects and advantages 95 of the invention will more fully and clearly appear from the description and claims hereinafter following.

In the drawings forming a part of this specification, Fig. 1 is a side elevational view of a 100

portion of a box car showing my improved door construction applied thereto. Fig. 2 is an enlarged, broken vertical sectional view corresponding substantially to the line 2-2 of Fig. 1. Fig. 3 is an enlarged horizontal sectional view corresponding to the line 3-3 of Fig. 1, the parts in this figure being broken away in order better to accommodate the figure on the sheet. Fig. 4 is an enlarged 10 detailed horizontal sectional view of a modified form of a rear edge construction of a door. And Fig. 5 is a fragmentary horizontal sectional view of the forward edges of two doors showing still another embodiment 15 of my invention.

Referring first to the construction illustrated in Figures 1 to 3, two doors are shown, one of which, indicated at A, may be termed the auxiliary door of a double outside sliding 20 type of door construction, and the door B may be designated as the main door of the double door construction. Each of the doors A and B is of the top-hung type, the door A being provided with hanger brackets, 10-10, while 25 the door B is provided with hanger brackets 11-11, the brackets carrying rollers in the usual way, adapted to ride upon a suitable track 12 mounted on the side of the car above the door opening. In Fig. 3 is illustrated a 30 common arrangement of car structure for defining a side door opening, and, as shown, one side door post is indicated at 130, and the opposite side door post at 140, said posts being reinforced by Z bars 13 and 14, the inner 35 flange of each of which is secured to the side wall structure 15 of the car body. Each of the Z bars 13 and 14 is provided with a guard, or spark strip member in the form of an angle 17, each angle member having an outwardly projecting flange 18, the extremity 40 of which is bent back upon itself as indicated at 19 in the drawing.

The auxiliary door A is of the sheet metal type and has the main body portion thereof 45 comprised of a plurality of panels 20-20 with their horizontal edges overlapped and riveted, the sheet metal of the door being provided with outwardly extending horizontally disposed corrugations 21, the body portion 50 of the door thus formed being provided, adjacent its front edge, with a vertically extending off-set 22 which extends outwardly from the main plane of the door at an angle thereto. The outer end of the angular off-set 55 22 is integrally formed with an off-set portion 23 disposed outwardly of the plane of the main body portion of the door but substantially parallel therewith, the off-set 23 being integrally formed with a wall 24 ex- 60 tending toward the edge of the door and inwardly toward the plane defined by the main body portion thereof, the angular off-set 22, the parallel off-set 23 and the inclined wall 24, defining a vertical corrugation adjacent 65 the edge of the door into which the ends of

the horizontal corrugations 21 merge. Secured to the forward edge of the door A is a reinforcing bar preferably of heavier material than the sheet metal of the body portion of the door. Said bar preferably comprises a rolled section, originally of T cross-section, the stem of the T being indicated by the reference character 25, while the oppositely extending head flanges of the T section are designated by the numerals 26 and 27. In 70 fabricating the T section with the forward section of the door A, the stem 25 is disposed substantially at right angles to the main plane defined by the body portion of the door and extends outwardly therefrom, the extremity of the stem being bent to provide a flange portion 28 which is secured to the parallel off-set section 23 by means of rivets indicated at 29. The head flange 26 of the T section lies substantially in the plane defined by the main body portion of the door, the sheet metal of said body portion being slightly off-set as indicated at 30, to accommodate the flange 26 in this position, said flange being secured to the body portion by 80 rivets indicated at 31. The head flange is provided with a plurality of openings 32 through which a bucking tool may be extended to facilitate the formation of the rivets 29 which secure the stem flange 28 to 85 the off-set or under surface of the crest of the edge corrugation. The opposite head flange 27 also lies in a plane common with the main plane of the body portion of the door and with the plane defined by the head flange 26. The wall 24 of the edge corrugation is secured to the head flange 27 by means of rivets indicated at 33. The flange 27 extends beyond the termination of the sheet metal of the wall 24 and is bent outwardly 90 to provide a curved sealing member 33a adapted to co-operate with the door B. Secured to the inner surface of the T member is a nailing block support or metal post 34, which is in the form of an angle member 95 having its flange 35 secured to the flange 27 by means of the rivets 33, the free edge of the flange 35 being curved inwardly as indicated at 35a, to facilitate engagement with the door B. The flange 36 of the member 34 extends substantially at right angles to the main body portion of the door and inwardly thereof, and is provided with a reinforcing angular section 37. A brace 38 is provided which 100 extends from adjacent the end of the flange 26 of the T member, where it is secured, in an inclined direction toward the inner end of the flange 36 of the support 34, the inner end of the brace 38 being riveted to the flange 36 as indicated at 39. A nailing block 40 is secured to the support 34 by bolts or other suitable means. Brackets 41 will preferably be mounted upon the threshold and lintel of the door frame and each provided with a stop 41 engage- 105 110 115 120 125 130

able with the nailing block 40, to limit forward movement of the door A, as shown in Fig. 3 of the drawing.

The rear edge of the door A is provided with a vertical corrugation similar to the front edge corrugation, the rear corrugation being defined by an angular portion 43, parallel off-set portion 44, outer inclined wall 45 and marginal section 46.

16 The reinforcing bar at the rear end of the door is somewhat similar to the T bar at the front edge of the door, comprising a stem 47, having a flange 48 secured to the off-set 44 by rivets 49, it being noted that the flange 48 of the stem is oppositely disposed with reference to the flange 28 of the front T member. The head flange 50 is secured to the body portion of the door in the same manner as the flange 26 of the front T section, by means of rivets indicated at 51. The flange 50 is provided with openings 52 for the insertion of a tool in forming the rivets 49. The head flange 53 of the rear T section is riveted to the marginal portion 46 of the wall 45 by means of rivets 54. Integrally formed with the inner surface of the head flange 54 is a curved spark seal flange 55 which co-operates with the spark seal member 19 when the door is closed, it being noted that the door is so formed that 30 no rivet heads are in the way of the proper operation of the door, due to the slightly extended width thereof, so that the rivets can be placed outwardly of the spark seal member 55; also, there is no necessity for the utilization 35 of countersunk rivets in securing these members in position. The reinforcing elements at the front and rear of the door are provided with integral connecting members at their tops and bottoms, as indicated at 550, 40 the flange 25 of the front edge member, and the flange 47 of the rear edge member, being cut off at top and bottom, as indicated at 551, to permit the sheet metal of the adjacent panels of the door to be brought inwardly to 45 lie against the transverse members 550 and be secured thereto, as indicated at 552.

The door B is similar in construction to the door A just described. It is slidably mounted to move in a plane common with the plane of the door A, but in the opposite direction, and is slightly greater in width than the door A. The forward edge of the door B co-operates with the forward edge of the door A in forming a weather seal, and is provided with a T member connected to the sheet metal of the body portion of the door, to provide a tubular formation in the same manner in which the tubular formation at the forward edge of the door A is provided; these formations extending vertically along the forward portions of the two doors and projecting outwardly beyond the main plane of each door; similar reference characters are utilized to designate 55 the corresponding parts of the forward por-

tion of the doors A and B, as well as other similar portions of said doors. At the forward edge of the door B, the flange 27 of the T member is for the most part disposed in the main plane of the door, and extends 70 toward the other door A; the extremity of the flange 27 is provided with a curved portion 56, which fits beneath the sealing member 33 on the door A, it being noted that the interengaging portions 33 and 56 of the doors lie inwardly of the plane defined by the crests 75 of the corrugations or tubular formations adjacent the forward edges of the two doors A and B. By this arrangement the ridgelike constructions provided by the tubular formations will serve to deflect the wind and prevent the same driving rain into the joint. Except for the parts of the door mentioned above, it is the same in construction as the door A; the door post arrangement at the 80 forward edge of the door A, of course, is omitted from the door B, since the latter is designed to co-operate with the door post arrangement of the door A during operation 85 of the door B. When the car is used for grain 90 and lading of a similar character, boards may be nailed to the post 40 and to the car structure adjacent the posts 130 and 140, in the usual manner.

Referring now to Fig. 4 of the drawings, a 95 slightly different embodiment of the invention is contemplated. In this construction the parts are similar to the rear edge construction of the door A, except that the flange 48 on the stem of the T member is turned 100 in the opposite direction to that in which the flange 48 is disposed; said flange, indicated at 57, being turned outwardly toward the rear edge of the door. In this embodiment of the invention, it will be appreciated that the construction shown at the rear edge of the door 105 may be utilized in connection with any edge of the door, either top, bottom or forward edge, by omitting the flange 55 where necessary or desired.

Referring now to Fig. 5, a somewhat different embodiment of the construction of the forward edges of the doors A and B is contemplated. In this construction the wall 24 is omitted and the offset 58 of the angular off-set 22 terminates upon the flange 28, as shown. The head flange 27 is of somewhat shorter length than the flange disclosed in connection with Figs. 1 to 3, and the outer end thereof is bent outwardly from the inwardly bent portion of the flange 35 of the nailing post support, as indicated at 59, to provide a groove 60. The forward end of the door B likewise has the offset 22 terminating at the flange 28 of the T member, as indicated at 61. The head flange 27 of the T member, instead of being curved, as indicated at 56, is straight, 120 to provide a portion 62 which fits into the groove 60, to provide a weather seal. Attention is called to the fact that by reason of the 125 130

provision of the ridgelike formations adjacent the forward edges of the doors A and B in this embodiment of the invention, the interengageable portions 35, 59 and 62 lie in side of the plane defined by the outer surfaces of the ridgelike formations, because of their location substantially in the plane defined by the main plane of the body portions of the doors. It will be understood that the top, bottom and rear edges of the doors A and B, as shown in Fig. 5, may be of the same character as the edge constructions there shown, said constructions being adapted for use in connection with any, or all, edges of said doors.

By the above described arrangement, it will be appreciated that a door construction is provided, having edges reinforced and fabricated in such manner as to counteract the tendency of the reinforcing bars to twist, and wherein the reinforcing bars are well able to withstand the blows to which they are subjected. By providing the apertures in the reinforcement bars, all difficulty which hitherto has existed in riveting the sheet metal to the reinforcing bars is obviated, and the rivets may be placed at the most advantageous points to obtain the maximum strength and to facilitate assembling of the door parts.

By forming the spark seal integrally with the reinforcing members, a construction having greatly increased strength and durability is provided, and due to the disposition and formation of the sealing members a recess is provided in one door edge which is adapted for the reception of projecting means on the other door, to form a joint which lies substantially in the plane defined by the main body portions of the two doors, so that the tubular formations adjacent the sealing members, which project outwardly beyond the main plane of the door a considerable distance, serve to deflect rain and prevent the same entering the joint.

While I have herein shown and described what I consider the preferred manner of carrying out the invention, the same is merely illustrative, and I contemplate all changes and modifications which come within the scope of the claims appended hereto.

I claim:

1. A door of the character described, comprising a main body portion of sheet metal having a reinforced vertical edge construction comprising a T member, the stem of which is disposed substantially at right angles to the main plane of the main body portion of the door, the stem of said T member being deformed to provide a flange disposed at an angle with respect to the remainder of said stem, said flange being secured to the sheet metal of the main body portion at one side of the main plane thereof, one of the head flanges of said T being secured to the body portion substantially in

the main plane defined by the body portion, and the other head flange extending outwardly from said stem, said outwardly extending flange being deformed to provide a vertically disposed weather sealing member.

2. A door of the character described, the combination with a main body portion comprised of sheet metal and a T shaped reinforcing section, the stem of which extends substantially perpendicular to the main plane of the main body portion of the door, said stem having its end portion deformed to provide a flange, and the head flanges of said T element being arranged substantially in the plane defined by the main body portion of the door, said body portion being secured to both of said head flanges and extending over the angular portion of said stem and being rigidly secured to the latter.

3. A door of the character described, comprising a reinforced metallic body portion having an edge corrugation; of a reinforcing element in the form of a T member having its stem arranged substantially at right angles to the main plane of the body portion of said door, said T member having its head flanges secured to the body portion of said door at opposite sides of said corrugation, and the stem of said T member extending into said corrugation and having an angular portion thereon rigidly connected to said corrugation at the peak thereof.

4. As an article of manufacture, a reinforcing element provided with a plurality of angular portions to which parts of a car door may be riveted, certain of said angular portions being provided with openings for the reception of riveting tools to permit riveting of parts of the door to a plurality of angular portions of said reinforcing element.

5. A door of the character described, comprising a main body portion having an off-set therein, and a reinforcing element at the rear edge of said body portion, said reinforcing element being of T form with the stem thereof disposed substantially perpendicular with reference to the main plane of the body portion of said door, and said stem having its end bent to form a flange, said body portion being connected to the head flanges of said T member, and said off-set connected to the flange on said stem, one of the head flanges of said T member being provided with a spark seal section.

6. As an article of manufacture, a reinforcing element for use in connection with metallic car doors, said element being substantially of T formation with a stem and head flanges, the stem of which is bent to provide a securing flange, and one of said head flanges provided with an integrally formed extension to provide a spark seal.

7. A car door comprising a main body portion and including reinforced front and rear edge constructions, the front edge construc-

tion having fabricated therewith a reinforcing element substantially of T form, and the rear edge also having fabricated therewith a similar member, the T member at the rear edge of said door being provided with an integrally formed spark seal section and the stems of both T-members extending perpendicular to the main plane of the door.

8. A car door comprising a main body portion and including reinforced front and rear edge constructions, the front edge construction having fabricated therewith a reinforcing element substantially of T form, and the rear edge also having fabricated therewith a similar member, the T member at the rear edge of said door being provided with an integrally formed spark seal, and the stems of said rear member and said front member being bent and rigidly secured to an off-set adjacent the edges of the main body portion of the door, said main body portion being secured to the head flanges of each T member at opposite sides of each of said off-sets.

9. In a construction of the character described, the combination with a main door and an auxiliary door, each of said doors being provided at their meeting edges with reinforced edge constructions having T members fabricated within each edge construction, the stem and one head flange of each member being rigidly secured to the main body portion of the related door, and the remaining head flanges projecting outwardly toward each other and being bent to form overlapping portions to provide a weather seal.

10. A door of the character described, comprising a main body portion; a reinforcing element substantially in the form of a T member, the stem being disposed substantially perpendicular with reference to the main body portion of the door, and the head flanges lying substantially in the main plane defined by the main body portion of the door, said body portion overlapping and being secured to the stem portion of said member; and a nailing block support rigidly affixed to the head flanges of said reinforcing element and extending inwardly of the main plane of said door.

11. A door of the character described, comprising a main body portion; a reinforcing element substantially in the form of a T member, the stem of said T member being disposed substantially perpendicular with reference to the main body portion of the door, and the head flanges of said T member lying substantially in the main plane defined by the main body portion of the door, said body portion being secured to said stem and head flanges of said member and a nailing block support rigidly affixed to the head flanges of said reinforcing element and extending inwardly of the main plane of said door, a portion of said nailing block support, and one

head flange of said member being arranged to provide a recess for the reception of the edge of a co-operating door.

12. As an article of manufacture, a reinforcing edge bar for a door having the main portion thereof comprised of sheet metal, said bar including two integrally formed sections arranged parallel to each other and spaced apart, one of said sections being of lesser width than the other, the section of greater width being provided with apertures therewith in alignment with said narrower section, whereby portions of the sheet metal of the main part of the door may be secured to both of said sections, and access to the securing means to the narrower section being had through said apertures.

13. As an article of manufacture, a reinforcing edge bar for a door, having the main portion thereof comprised of sheet metal, said bar including integrally formed portions disposed in spaced relation with one overhanging the other, said bar being provided with an integral spark sealing section, one of said portions being provided with apertures therewith in alignment with the other portion, whereby parts of the sheet metal of the main part of the door may be secured to both of said portions, access to the securing means for said other portion being had through said apertures, said sealing section being arranged clear of said apertures.

14. As an article of manufacture, a reinforcing member for a vertical edge of a door, said member having a main web, a flange extending from one side thereof near one edge of the web and adapted to provide a weather seal, and a flange extending from the opposite side of the web near the other edge of the web, said last named flange having the free edge portion thereof bent into approximate parallelism with the web and to which is adapted to be secured a portion of a door sheet.

15. A reinforced sheet metal door for cars, the same comprising: a main body portion comprised of sheet metal having a vertically extending corrugation adjacent each vertical edge of the door; and a reinforcing bar at each vertical edge, each of said bars having a main web bridging the open mouth of the corrugation and secured to the sheet metal along opposite sides of the corrugation, each said bar having also a flange projecting therefrom into the corresponding corrugation, each flange having an outer bent portion extending parallel to the web and secured to the crest of the corrugation.

16. A reinforced sheet metal door comprising: a main body portion formed of sheet metal and having an outwardly disposed corrugation extending vertically along one edge thereof; and a reinforcing bar having a web and a flange extending outwardly therefrom,

- said web bridging the open mouth of the corrugation and secured to the sheet metal along opposite sides of the corrugation, said flange extending within the corrugation and having a bent outer portion arranged parallel to the web, said outer bent portion being secured to the crest of the corrugation.
17. An auxiliary reinforced metal door for a double door car opening, said auxiliary door comprising: a main body portion composed of sheet metal and having a vertically extending corrugation therein along the front edge of the door; a reinforcing bar for said front edge of the door comprising a main web and an outwardly extended flange, the web bridging the open mouth of the corrugation and secured to the sheet metal along opposite sides of the corrugation, the flange extending within the corrugation and having its outer portion bent to parallelism with the web and secured to the crest of the corrugation; an angular nailing strip support having one flange thereof secured to the web of the bar and marginal portion of the sheet metal, another flange of said support extending inwardly from the web of the bar; and a diagonally disposed brace secured along one edge of said inwardly extending flange of the support, the opposite edge of said brace being secured to the web of said bar and the sheet metal of the door inwardly of the corrugation.
18. An auxiliary door for a house car double door opening, said auxiliary door comprising a main body portion of sheet metal having a portion thereof, adjacent the forward edge, outwardly offset from the main plane of the door; a vertically disposed reinforcing member for the forward edge of said door, said member having a web disposed substantially in the main plane of the door with one edge thereof secured to the main sheet metal portion inwardly of said offset, said member having a flange on its outer side disposed substantially perpendicular to the web and extending from the web to said offset portion of the main sheet member; and a metal post of angular cross section secured to the inner face of said web and to which a nailing strip is adapted to be secured.
19. An auxiliary door for a house car double door opening, said auxiliary door comprising a main portion of sheet metal having an outwardly offset vertically extending corrugation therein for its front edge; a reinforcing member for said front edge of the door, said member having a web bridging the mouth of the corrugation and secured to the sheet metal along opposite sides of the corrugation, said member having also a flange disposed substantially perpendicular to the web and extending from the web to the crest of the corrugation; a metal post of angular horizontal cross section secured to the inner side of said web and to which a nailing strip

is adapted to be secured; and bracing means extending between said web and post.

In witness that I claim the foregoing I have hereunto subscribed my name this 21st day of February, 1928.

FRANK DITCHFIELD.
